WALL PAPER CLEANING DEVICE

John S. Lincoln, Des Moines, Iowa

Application April 24, 1940, Serial No. 331,346

6 Claims. (Cl. 15—219)

There is in general use a wall paper cleaning compound of a plastic nature, about the consistency of bread dough. It is generally used by grasping it in an operator's hand and wiping it over the paper to be cleaned, and after one or two such operations it is kneaded by the operator's hands to withdraw the soiled surface into the mass. This kneading operation is necessarily hard and slow work.

The object of my invention is to provide a device of simple, durable and inexpensive construction in which a quantity of wall paper cleaner is placed and a straight-edged portion thereof projected beyond the cleaner holder, and whereby the operator may grasp the handle of the cleaner and readily and easily wipe a relatively large area of wall paper in a single operation, and may conveniently and easily reach from a position standing on the floor of a room and clean all of the walls and ceiling.

More specifically, it is my object to provide a device of this class in which, when the projected portion of the cleaner has been used and become soiled, a very rapid and easy manual operation will move another portion of the cleaner to position to be projected beyond the holder and move the previously soiled portion toward the center of the mass of cleaner and apply a kneading operation to the cleaner and finally project a previously unused portion in a straight edged pattern beyond the holder.

In the accompanying drawing—

Figure 1 shows a perspective view of my improved wall paper cleaning device;

Figure 2 shows a transverse sectional view of the same;

Figure 3 shows a detail transverse sectional view and illustrates the position of the cleaning plastic within the holder when the compressing and mixing member has been moved to open position and before the plastic has been rotated within the holder; and

Figure 4 shows a longitudinal sectional view on the line 4—4 of Figure 2.

My device comprises a cylindrical holder 10 having closed ends 11. At one side of the holder there is formed a longitudinal slot at 12, through which the plastic cleaner is projected for cleaning purposes. Adjacent this slot 12 there is a relatively large opening at 13 for use in inserting cleaning plastic into the holder. A handle 14 is fixed to the holder.

Extended longitudinally through the central portion of the holder is a shaft 15 having at one end a ratchet wheel 16. A manually operated

lever 17 is mounted on the shaft and provided with a spring actuated pawl 18 to engage said ratchet for rotating the shaft. Fixed to the shaft on the interior of the holder adjacent each end is a disc 19 having a series of plastic engaging pins 20 projected inwardly toward the transverse center of the holder, and fixed to the shaft is a spirally arranged dough-kneading member 21.

10 Pivoted to the holder adjacent the refilling opening 13 is a cleaner compressing and mixing device comprising a curved wall 22 extended lengthwise of the holder throughout substantially the entire length thereof, and when in closed position, extended inwardly toward the longitudinal center of the holder. At the inner end of this wall 22 is another wall 23 which extends outwardly to the inner wall of the holder, and when this device is in its closed position, as shown in 15 Figure 2, these two walls substantially cover the entire opening 13. A handle 24 is fixed to the wall 23.

In practical operation the handle 24 is moved to position for moving the wall 23 outwardly to 25 position for uncovering the refilling opening 13. When the plastic has been inserted in the holder the handle 24 is moved to position adjacent the handle 14 and they are shaped so that both handles may be conveniently grasped in an operator's hand. When this compressing and mixing member has thus been forced into its closed position it will displace a quantity of the cleaning compound within the holder and force it outwardly through the opening at 12.

30 In Figure 3 the configuration of the plastic cleaner when in position for use is illustrated. By this compression method the outer surface of the projected portion of the plastic arranges itself along a substantially straight line, and when 35 this is applied to wall paper and wiped over the wall paper it is pressed by the operator against the wall paper so that the plastic cleaner adapts itself to the contour of the paper and completely wipes the entire surface covered by the wiping action. In practice, I have found that when 40 this has been done with one wiping operation, the paper is thoroughly cleaned and all of the dirt upon the paper adheres to the plastic cleaner.

45 After this operation the operator moves the handle 24 to position bringing the wall 22 to a position substantially in line with the wall of the holder. This forms an open space, as shown at 50 25 in Figure 3, within the body of the plastic cleaner. Then the operator grasps the handle 17 and rotates the shaft 15. When this has been

done the plastic-engaging fingers 20 will grip the mass of material and rotate it a small part of a revolution in the direction of the arrows shown in Fig. 3. This will first withdraw the projected portion of the plastic cleaner due to the adhesive quality of the cleaner, and move the soiled portion of the plastic cleaner toward the right of the opening through which it was previously projected. Then, when the compressing and mixing member is again moved to its normal position, the previously soiled section of the cleaner will be moved inwardly toward the longitudinal center of the holder. Obviously, this operation may be very quickly and easily performed because it requires only a small amount of power to open and close the compressing and mixing member, and only a slight amount of power to rotate the shaft 15 the small part of a revolution. However, with these two slight operations which must be performed after each wiping action of the cleaner, the cleaning plastic is thoroughly kneaded and all of the soiled surfaces thereof are worked into the mass of the cleaner.

I have found in practice that with my improved cleaning device a given quantity of the plastic cleaner will thoroughly clean a much larger area of wall paper than is practicable with the use of the cleaning plastic by hand and the imperfect kneading operation which is usually performed by the operator's hands under such conditions.

When the soiled section of the cleaning plastic has been moved toward the center of the holder, then each time that the lever 17 is operated, an additional kneading operation is applied to the plastic compound by the kneading spiral 21.

Devices of this class are commonly known to the trade as wall paper cleaners. They, however, are useful in the cleaning of such things as window shades, lamps, tapestries, tinted walls, pictures, kalsomined walls, etc.

I claim as my invention:

1. In a wall paper cleaning device, the combination of a holder for a plastic cleaner compound, said holder having a longitudinally arranged slot at one side, a handle for the holder, a rotatable cleaner-engaging member at the central portion of the holder having a handle on the exterior of the holder by which the mass of cleaner within the holder may be rotated to present new surfaces thereof to the said longitudinal slot, said cleaner rotating device comprising a rotatable shaft extended through the longitudinal central portion of the holder, and fingers carried by the shaft and extended from the ends of the holder toward the transverse center thereof.

2. A wall paper cleaning device, comprising a holder of cylindrical form having a longitudinally arranged slot at one side, a handle fixed to the holder, a cleaner compressing member hinged to the holder at one side of the slot and movable from position adjacent the wall of the holder toward the central portion of the holder, and a handle fixed thereto and projected beyond the holder.

3. A wall paper cleaner, comprising a substantially cylindrical holder, having a longitudinally arranged slot at one side and also having an opening at one side through which cleaning plastic may be inserted, a handle for the holder, a cleaner pressing and mixing device hinged to the holder at one side of the filling opening, and shaped to close the filling opening when in one position of its movement and capable of move-

ment to position for clearing the opening, a portion of said compressing and mixing device being extended inwardly from the wall of the holder toward the longitudinal center thereof, and a handle fixed to the compressing and mixing device.

4. In a wall paper cleaning device, the combination of a holder for a plastic cleaner compound, said holder having a longitudinally arranged slot at one side, a handle for the holder, a rotatable cleaner-engaging member at the central portion of the holder having a handle on the exterior of the holder by which the mass of cleaner within the holder may be rotated to present new surfaces thereof to the said longitudinal slot, and a cleaner compressing and mixing device extended longitudinally of the holder and movable from a position adjacent the wall of the holder inwardly toward the longitudinal center thereof for forcing an outer segment of the cleaner into the central portion of the mass of cleaner, and when moved to its outer position, forming an open space in the mass of cleaner to permit ready withdrawal of the previously projected portion of the cleaner when the cleaner is rotated.

5. A wall paper cleaning device, comprising a hollow receptacle for a plastic cleaning compound and formed with a longitudinal slot through which a portion of the plastic may be projected, a plastic compressing member connected to the receptacle and movable toward and from the longitudinal center of the receptacle for forcing a portion of the plastic to project through the slot when the compressing member is moved inwardly, and forming a longitudinal depression in the plastic material, and means for rotating the mass of plastic material within the receptacle whereby when the compressing member is moved outwardly and the plastic material rotated within the receptacle, the previously projected portion of the plastic will be moved by engagement with the receptacle wall adjacent the slot inwardly toward the longitudinal center of the receptacle, thereby forcing plastic material at said depressed portion outwardly and effecting a kneading operation.

6. A wall paper cleaning device, comprising a hollow receptacle for a plastic cleaning compound and formed with a longitudinal slot through which a portion of the plastic may be projected, a plastic compressing member connected to the receptacle and movable toward and from the longitudinal center of the receptacle for forcing a portion of the plastic to project through the slot when the compressing member is moved inwardly, and forming a longitudinal depression in the plastic material, means for rotating the mass of plastic material within the receptacle whereby when the compressing member is moved outwardly and the plastic material rotated within the receptacle, the previously projected portion of the plastic will be moved by engagement with the receptacle wall adjacent the slot inwardly toward the longitudinal center of the receptacle, thereby forcing plastic material at said depressed portion outwardly and effecting a kneading operation, and means operatively connected with the said rotating means for forcing the central portion of the plastic material toward one end of the receptacle, thereby performing an additional kneading operation.
